United States Patent Office

Des. 178,469
Patented Aug. 7, 1956

178,469

BUILDING

Charles E. Volk, Great Falls, Mont.

Application November 26, 1954, Serial No. 33,250

Term of patent 14 years

(Cl. D13—1)

FIG. 1

FIG. 2

FIG. 3

FIG. 4

FIG. 5

Figure 1 is a perspective view of a building embodying my new design;

Figure 2 is a side elevational view thereof;

Figure 3 is a front elevational view thereof;

Figure 4 is a rear elevational view thereof; and

Figure 5 is a top plan view thereof.

The dominant characteristics of my new design are shown in the full lines of the drawing.

I claim:

The ornamental design for a building, as shown and described.
